[57] CLAIM

The ornamental design for a sandbox, wading pool or similar article, as shown.

DESCRIPTION

FIG. 1 is a top plan view of a sandbox, wading pool or similar article showing my new design;

FIG. 2 is a front elevational view thereof;

FIG. 3 is a rear elevational view thereof;

FIG. 4 is a side elevational view thereof, the side opposite being a mirror image of the side shown;

FIG. 5 is a top perspective view thereof; and

FIG. 6 is a bottom perspective view thereof.

FIG.1
